UNITED STATES PATENT OFFICE

108,074

DESIGN FOR A BOTTLE

Robert C. Gennaro, Vincent L. Gennaro, and Emil L. Gennaro, Hazelton, Pa.

Application October 16, 1937, Serial No. 72,244

Term of patent 14 years

To all whom it may concern:

Be it known that we, Robert C. Gennaro, Vincent L. Gennaro, and Emil L. Gennaro, citizens of the United States, residing at Hazelton, in the county of Luzerne and State of Pennsylvania, have invented a new, original, and ornamental Design for a Bottle, of which the following is a specification, reference being had to the accompanying drawing, forming part thereof.

We claim:—

The ornamental design for a bottle, as shown.

ROBERT C. GENNARO.
VINCENT L. GENNARO.
EMIL L. GENNARO.
